UNITED STATES PATENT OFFICE

2,199,703

STREET SWEEPER

Frank G. Hough, Chicago, Ill.

Application October 5, 1938, Serial No. 233,353

2 Claims. (Cl. 15—84)

This invention relates to street sweepers and more particularly to the type of sweepers wherein provision is made to pick up the sweepings and deposit them in a suitable bin in the sweeper and generally known as a pick-up type of street sweeper.

The principal object of the invention is to provide a pick-up type street sweeper of simple and substantial design which will perform its intended functions in an efficient manner under all operating conditions.

Another object is to utilize a commercially built tractor in the construction of a pick-up type street sweeper wherein the tractor motor, through the rear or drive wheels of the tractor, provides the motive power of the sweeper and the tractor motor also drives the operating parts of the sweeping elements.

A further object is to utilize a commercially built tractor in the construction of a pick-up type street sweeper and distribute the entire weight of the tractor and of the gutter broom and its associated parts on the rear axle of the tractor which becomes the front axle of the sweeper, and the weight of the main sweeping element, water tank and contents, conveyor and dirt receiving bin and contents, and the associated framework between the sweeper's front and rear axle whereby the weight of the tractor and gutter broom and its associated parts are more than counterbalanced over the tractor rear axle by the weight of the main sweeping element, water tank, conveyor, dirt receiving bin, and the associated framework.

A still further object is to utilize a commercially built tractor in the construction of a pick-up type street sweeper by eliminating the front wheels and axle thereof and building the main sweeping element, water tank, conveyor, dirt receiving bin and associated framework rearward of the rear axle of the tractor and a steering wheel at the extreme rear of the sweeper.

Referring to the accompanying drawings wherein a selected embodiment of the invention is illustrated:

Fig. 1 is a side elevation of the right-hand side of a sweeper embodying the invention and wherein the sheet metal cover for the device has been removed to better illustrate the arrangement of parts;

Fig. 2 is a side elevation of the left-hand side of the sweeper showing the cover in section;

Fig. 3 is a detail view of part of the mechanism for transmitting power from the tractor motor to the main sweeping element;

Fig. 4 is a detail view showing the means for positioning the gutter broom, the full lines showing the position of the parts when the gutter broom is in inoperative position and the broken lines showing the position of the parts when the gutter broom is in operative position;

Fig. 5 is a front elevation showing some of the parts broken away; and

Fig. 6 is a plan view of the front end of the sweeper.

In constructing the sweeper of this invention I utilize an ordinary commercially procurable tractor of any of the various makes to be found on the market and eliminate the front axle and front wheels thereof. I may also use a tractor of the endless tread type by removing the endless treads and installing drive wheels on the rear of the drive shaft or axle thereof which is normally used in driving the endless treads. For the purpose of this description and the illustrations in the drawings I have shown the utilization of a wheel type tractor, however, comprising the usual rear or drive wheels 7 and a motor under the hood 8. I also utilize the steering wheel 9 and steering column 10 of the tractor but remove the connections to the front wheels of the tractor which normally steer the device and connect it to a pilot wheel 11, as will be more fully described hereinafter. A frame generally indicated by 12 has axle housing engaging members 13 and 14 at the front thereof and extending forwardly on both sides of the sweeper. The members 13 are adapted to be secured to the top of the rear axle housing of the tractor at the ends thereof, and the axle housing engaging members 14 are adapted to be secured to the bottom of the rear axle housing of the tractor at the ends thereof and substantially beneath the members 13. The members 14 have extensions 15 extending forwardly therefrom which are secured, by bolts 16, to the tractor frame 17, or in the event the particular tractor used is constructed without a frame then the extensions 15 are bolted directly to the block or crank case of the motor.

An upright frame member 18 is secured to the members 13 and 14 and has a main frame member 19 extending rearwardly therefrom and secured rigidly thereto. A pilot wheel yoke 20 is pivotally mounted at 21 in the frame at the rear end thereof, and the pilot wheel 11 has an axle 22 mounted in the yoke 20. A suitable quadrant and chain connection 23 comprising a quadrant pivotally mounted on the frame and a chain fixed to the periphery of the quadrant and adapted to ride thereon during operation of the connection

and engaging the yoke 20 to pivot the yoke upon pivotal movement of the quadrant, is used for controlling the directional movement of the wheel 11. The quadrant is connected to and operated by a crank arm secured thereto and to a steering rod 24 extending forwardly to a lever 25 rigidly secured to a countershaft 26. The countershaft is operatively connected by a rod 27, lever 28 and shaft 29 to the steering column 10. Thus it will be seen that operation of the steering wheel 9 will rotate the yoke 20 at its pivotal connection in the frame to swing the pilot wheel 11 to the right or to the left as may be desired for steering the sweeper.

15 A sweeping element such as a brush 30 is rotatably mounted in arms 31 at the sides of the sweeper. The arms 31 are pivotally mounted on brackets 32 which are rigidly secured to the frame. The brush is rotated in the direction of the arrows, Figs. 1 and 2, by power from the engine of the tractor. A shaft 33 suitably connected to the rear power take-off of the tractor operates suitable gears in a gear box 34 to drive shaft 35 which, in turn, drives suitable gears in a gear 20 box 36 to drive the cross shaft 37, Fig. 2. A sprocket 38 is mounted on the end of shaft 37 at one side of the sweeper and drives another sprocket 40 on a shaft 41 through chain 39. The shaft 41 is mounted in the brackets 32. The 25 shaft 41 is the main drive shaft for the brush 30 and for the elevator generally indicated by 42 and to be described hereinafter. It will also be noted that the arms 31 do their pivoting about the shaft 41. The drive shaft 41 drives a sprocket 43 through a chain 44. The sprocket 43 is rigidly secured to the axle of the brush 30.

30 The elevator 42 is of any suitable construction but is preferably of that type generally having endless chains at either side thereof and buckets 40 arranged between and secured to the chains at their ends so that dirt swept up by the brush under the elevator will, in the operation of the chains, be carried upwardly by the buckets to the top of the elevator and when the buckets go over the top the dirt will be discharged into a suitable bin 45 through an opening 50 therein. The elevator chains are driven from the shaft 41 and a sprocket wheel 46 through the chain 47. The sprocket wheel 46 is mounted on a shaft 48 which is secured in bearings 49 mounted on the frame 12. The entire elevator 42 is supported from the shaft 48 and is free to pivot slightly thereon.

35 A shoe 51 is arranged at either side of the machine just outside the ends of the brush 30. The shoe tends to keep the bristles of the brush in line and prevents their flaring outwardly at the ends of the brush and further confines the dirt swept by the brush to within the space defined by the ends thereof, and thus prevents the sweepings from being thrown sideways outside of the path of travel of the brush. The shoes are pivoted at 52 to arm 53 which themselves are pivoted at 54 to brackets 55 secured to the frame 12.

40 The inherent weight of the brush shoe and bottom end of the elevator is more than it is desired to have resting on the ground during a sweeping operation and hence I provide springs to relieve a predetermined portion of this weight. Springs 56 are secured at one end to the frame 70 and at the other end to chains 57, which chains are also secured to the arms 31 at or near the mounting of the axle for the brush. Thus part of the weight of the brush is carried by the springs 56 and enables the brush to more readily 75 follow the contour of the road surface being

swept. Springs 58 are likewise secured to the frame at one end and to chains 59 and 60 at their other ends. Chains 59 are also secured to the housing for the elevator and chains 60 are secured to the shoes 51. Thus part of the weight 5 of the shoes 51 and of the bottom end of the elevator 52 are carried by the springs 58.

It is desirable to remove the brush and shoe from contact with the ground when transporting the machine from one point to another when 10 sweeping between the points is not desired. Under the same circumstances it is desirable to raise the bottom end of the elevator from its normal position in close proximity to the ground to avoid damage thereto by any object which may 15 be in its path. To thus raise the brush I provide an hydraulic ram 61 secured to the frame and operable through a suitable hydraulic pump connected to the tractor motor and a valve under control of the operator and a pipe line 62. The 20 ram is connected to a bell crank 63 pivoted on a shaft 64 extending transversely of the machine and mounted on the frame. The other end of the bell crank 63 and a lever 65 on the opposite end of the shaft 64 have chains 66 secured thereto. The chains 66 are also secured to the arms 31. Opening of the valve in the pipe line 62 by the operator introduces the fluid into the ram 61 forcing the plunger thereof downwardly and pivoting the bell crank 63 and rotating the shaft 30 64 to raise the chains 66 and the arms 31 and the brush 30 so that the brush will rise out of contact with the ground. The chains 59 and 60 are also secured to the chains 66 so that when 35 the chains 66 are raised by operation of the ram 61 the chains 59 and 60 will raise the shoes 51 at the lower end of the elevator 42. The links of all of the chains are so adjusted that the brush will rise slightly in advance of the shoes 51 and the shoes 51 will rise slightly in advance of the 40 bottom of the elevator 42. This is for the reason that it is desirable to raise the brush slightly before the shoes start to rise and it is also desirable to raise the shoes slightly before the lower 45 end of the elevator starts to rise, thus assuring that each of the elements are out of the way before the following element starts to move. Wear on the brush bristles and on the ground engaging portion of the shoes may be compensated for by 50 changing the engaging links of the chains.

55 The bin 45 is provided at its lower end with a door 67 pivoted at 68 to the bin. The door is normally kept in closed position by a chain 69 extending over the free end of the door and secured on one side to the frame at 70. The chain passes through suitable guides 71 fast at the free end of the door. The chain 69 passes about a roller 72 secured in the frame and about another roller 73 secured on the end of an hydraulic ram 74. The chain after passing about the 60 roller 73 is securely fastened to the frame at 75. The ram 74 is operated similarly to the ram 61 through a suitable valve under control of the operator and pipe line 76. It will be seen that 65 when pressure to the ram is relieved the roller 73 will be retracted, slackening the chain 69 and permitting the door 67 to swing about its pivot at 68, thus opening the door and allowing the dirt in the bin to be discharged. Operation of the valve 70 will again send pressure through the pipe line 76 into the ram 74, extending the roller 73 outwardly to tighten the chain 69, thus closing the door 67.

75 My device embodies a somewhat conventional type of gutter broom 17 arranged forwardly of

the wheels 7 preferably on the right-hand side of the machine. A suitable gear box 78 is secured to the front power take-off and operates a shaft 79 extending through a housing 80 to another suitable gear box 81 to operate another shaft passing through the housing 82 to a third gear box 83 to operate a vertical shaft 84 on the bottom of which the gutter broom 77 is secured. It will thus be seen that the gutter broom obtains its rotative action from the front power take-off of the tractor. The housing 80 is rigidly secured to a frame member 85 extending forwardly from the tractor motor. The gear box 81 is connected to the housing 80 so that the broom 77, gear box 83 and housing 82 may be pivoted on the axis of the housing 80. A lever 86 extending back to a position where it is within easy reach of the operator is pivoted at 87 on a suitable bracket on the housing 80. The lever is also secured at 88 to a lever 89 rigidly secured to a sleeve 90 mounted on a shaft 91. The shaft 91 is rigidly secured to the frame member 85 and another frame member 92 is similarly arranged but on the opposite side of the tractor motor. The shaft 91 extends from the frame member 92 through the frame member 85 well out to the side of the machine, and it is on this latter end portion of the shaft that the sleeve 90 is mounted. A yoke 93 is secured to the sleeve and at its outer end has a roller 94 mounted therein. The housing 82 rests on the roller 94. When the operator pulls on the lever 86 when in the position shown in full lines in Fig. 1 and in broken lines in Fig. 4, the lever 89 is operated to turn the sleeve about the shaft 91, raising the lever 93 and roller 94 and consequently the housing 82, thus removing the broom 77 from contact with the ground. The lever 86 between the point 88 and its pivot 87 and the lever 89 provide an over-center device to hold the broom in raised position. At this point the levers take the position shown in full lines in Fig. 4. To place the gutter broom again in contact with the ground, the operator pushes on the lever 86 to return it to the broken line position shown in Fig. 4.

It is often desirable to dampen the road or street forwardly of the brooms so that the sweeping action of the brooms will not raise too much objectionable dust. To this end I provide a water tank 95 which is connected by a suitable pipe 96 to a pump 97 located at the front of the tractor and operated through a chain 98 from the shaft 79. The pump is connected by pipe 99 to a transverse pipe 100 having suitable nozzles 101 therein. The pipe 100 is arranged transversely of the sweeper at the extreme front thereof and the nozzles 101 are directed downwardly to spray the road or street in advance of the sweeper with water to dampen the dirt and dust thereon.

It will, of course, be understood that suitable provision is built into the tractor to control operation of the front and rear power take-offs so

that by operation of these controls operation of the broom 30, gutter broom 77 and pump 97 may be controlled by the operator of the sweeper. A cover or hood 102 of sheet metal is arranged over the top of the bin 45, conveyor 42, tank 95 and secured to the frame 12. The hood extends outwardly on both sides of the machine to approximately even with the axle for the wheels 7 and the axle for the wheel 11. Thus all of the working parts of the sweeper are enclosed to confine the dust stirred up by the broom 30.

It will readily be seen that my device provides for an efficient, simple and substantial sweeper, the cost of manufacture of which will be low and which is adapted to utilize a commercially procurable tractor for its motive and driving power.

While I have shown and described a selected embodiment of my invention it is to be understood that this is capable of variation and modification and I therefore do not wish to be limited to the precise details set forth but desire to avail myself of such changes and alterations as fall within the scope of the following claims.

I claim:

1. In a street sweeper of the pick-up type, the combination of a tractor including a motor, a driving axle, a housing for said axle rigidly secured to said motor, and a drive wheel on each end of said axle, said motor being arranged forwardly of and overhanging said axle housing, a 30 sweeper frame rigidly secured to said axle housing and extending rearwardly thereof, a main broom mounted on said frame, an elevator mounted on said frame with its lower end in cooperative relation with said main broom to receive dirt swept up by said broom and elevate the dirt to the top of the sweeper, means operatively connecting the broom and elevator to the rear power take-off of the tractor motor, a bin mounted on said frame and arranged in cooperative relation with the top end of said elevator to receive dirt therefrom, and a third wheel pivotally secured to said frame at the rear thereof, the weight of the tractor motor being more than counterbalanced over said tractor axle by the weight of the parts arranged rearwardly of the 40 axle.

2. In a street sweeper of the pick-up type, the combination of a tractor including a motor, a driving axle, a housing for said axle rigidly secured to said motor, and a drive wheel on each end of said axle, said motor being arranged forwardly of and overhanging said axle housing, a 50 sweeper frame having a pair of members on each side of said frame and extending forwardly thereof, one of said forwardly extending members of each pair secured to the top of said axle housing and the other member of each pair secured to the bottom of said axle housing, a sweeping element, and a third wheel, said element and third wheel mounted on said frame 55 and arranged rearwardly of said axle.

FRANK G. HOUGH.
